HERBERT R. BLISS AND LEONARD JOHNSTON, OF DETROIT, MICHIGAN; SAID JOHNSTON
ASSIGNOR TO GEORGE M. TUTTLE, OF NIAGARA FALLS, NEW YORK.

SHIPPING-CASE-STITCHING MACHINE.

1,174,943.

Specification of Letters Patent.

Patented Mar. 7, 1916.

Continuation of application Serial No. 793,994, filed October 8, 1913. This application filed August 13, 1914. Serial No. 856,522.

To all whom it may concern:

Be it known that we, HERBERT R. BLISS and LEONARD JOHNSTON, citizens of the United States, residing at Detroit, county of Wayne, State of Michigan, have invented a certain new and useful Improvement in Shipping-Case-Stitching Machines, and declare the following to be a full, clear, and exact description of the same, such as will enable others skilled in the art to which it pertains to make and use the same, reference being had to the accompanying drawings, which form a part of this specification.

This invention relates to machines for sealing fiber shipping-cases and has for its object a machine which will seal a fiber shipping-case with metallic fasteners. Heretofore it has been customary to seal fiber shipping cases by either gluing the flaps or else by pasting a paper strip over the flaps at their meeting edges. It has long been a desideratum to seal fiber shipping-cases with metallic fasteners such as staples or rivets. Wire stitching machines have long been used to stitch together meeting edges that form the sides of a fiber shipping-case, as it has been recognized that wire stitching affords a very much more secure fastening than gluing. Gluing, pasting or affixing a paper or sealing strip over a joint in a fiber shipping-case is objectionable because it is unsafe, for in cold weather the glue very often does not stick well, the flaps very often come apart in warm weather, and it is also possible to pry the case open and purloin some of its contents and replace the flaps by applying glue or additional sealing strips so that it is difficult or impossible to tell whether the contents of the case have actually been purloined or whether the loss was due to shortage caused by an error of the consignor.

The desirability of wire stitching or riveting in a fiber shipping-case has clearly been evidenced by the efforts made by inventors to secure such a result. For instance, it has been proposed to seal fiber shipping-cases containing Mason fruit jars by driving the staples through the flaps at places where they may strike the heads or bottoms of the jars and clenching the staples upon the tops or bottoms of the jars. It has also been proposed to use rigid end

members, such as wooden end frames and clench the rivets by bridging a steel rule from one rigid end member to the other rigid end member. It has also been suggested to rest the steel rule upon the contents, but a partially filled case could not be sealed in this way and injury would be done to the contents very often.

We have discovered that by using a blade anvil of suitable dimensions that the flaps may be secured over the anvil and the staples driven in and clenched against the anvil without materially bowing the flaps out as the anvil itself takes up scarcely any space. We can seal cases partially filled or completely empty. We have also discovered that this anvil may be rigidly supported at one end, and, notwithstanding its comparative thinness and its perceptible vibratory character, that it is capable of doing the work of clenching the fasteners without any support whatever except that afforded by the rigidly supported end. We have also discovered that the flexible character of this anvil actually assists in securing a tight closure of the case and in place of being a detriment is very advantageous.

In the drawings, Figure 1, is a side elevation of our machine. Fig. 2, is a perspective of the anvil showing its free end under a pair of fiber shipping case flaps. Fig. 3, is a fragmentary view of the shipping-case top showing the anvil in section and showing parts of the stitching head. Fig. 4, is a similar view showing the parts in the position they assume when the staple carrier strikes the anvil. Fig. 5, is a similar view showing the parts in the position they assume when the staple driver strikes the staple. Fig. 6, is a fragmentary view of the finished case showing how the flaps resume their former position and how they rest practically against the top of the case. Fig. 7, is a plan view of the shipping case and the anvil showing how first the flaps are drawn tightly together and the initial staples placed. Fig. 8, shows the same parts with the box turned around to place the staples in the opposite side.

A wire stitching machine is here shown, but of course any kind of machine for applying metallic fasteners could be used.

a represents the upright which is sur-

mounted by the horizontal arm *b*, which terminates at its free end in the stitching head *c*; the operating parts of this stitching head are not completely shown and will not be completely described as they are well known in the art. Wire spool *e* carries the wire from which the staples are formed. An electric motor *d*, has a pinion meshing with the gear wheel *f*, which connects with a shaft 5 that runs through the horizontal arm *b* by means of the clutch *h* operated by the lever and links *g*.

In Fig. 2 is shown the blade-like anvil; of course this may be varied in accordance 10 with the work to be done. We will, therefore describe only a suitable anvil for a case of given dimensions: take, for instance, one of twenty inches. Where such a case is to be sealed we preferably employ an anvil which 15 for the first three and one-half inches from the tip is one-quarter inch in thickness, which for the following six inches is five-sixteenths inch in thickness, and which for the succeeding six inches tapers from five-sixteenths of an inch to three-quarters, and which for the final six inches is three-quarters inch in thickness. This anvil is preferably three-and-one-half inches in width and is twenty-one and one-half inches long. 20 Fifteen inches of the anvil projects into free space from the holder *p*. The anvil is rigidly held to the holder by the wing nut *x*. It is made of tool steel and is provided with a clencher insert *i* of metal better adapted 25 to take the constant thrust of the staples. During the operation of stapling this anvil perceptibly flexes; in fact the amount of flexure varies between one-eighth and one-quarter of an inch. 30 Referring to Figs. 3, 4 and 5, the advantage of this flexure will be seen. In Fig. 3, the guide of the stitching head is designated *j*, the staple carrier *k*, the staple itself *l*, and the driver *m*, and the blade anvil *n*. It is 35 seen that the flaps are slightly bowed out when the blade anvil is inserted. In the sequence of operating steps of the stitching machine the staple carrier *k* comes down first, as shown in Fig. 4, and strikes the flaps 40 and forces the anvil down in the way shown in this figure. At this time the operator may push the sides of the case inwardly, as shown by the arrows of this figure. This causes the flaps to lie parallel to each other, 45 which makes possible the greatest possible amount of over-lapping and consequently the tightest fastening for the flaps that is possible. While in this position the driver *m* comes down and forces the staples through 50 the flaps and the staple is clenched on the anvil as shown in Fig. 5. 55 In Fig. 6, the condition of the flaps after the sealing has taken place is shown. It will be observed that the flaps lie contiguous to 60 the top of the sides of the case. Two condi-

tions contribute to this result, namely, the very thin anvil to do the clenching makes it possible to insert the clencher member between the flaps without materially bowing them out when the anvil is withdrawn, and the flexing of the anvil makes possible the fastening of the flaps so that there is practically no "bow" whatever. 70

In the claims herein following the dimensions of the anvil are fixed by reference to 75 the work to be done, namely the fastening of the flaps without materially bowing them out. The seeming indefiniteness of such description quickly disappears when the size of the case is known for it may be easily calculated what would be the proper size of the anvil to use and give the necessary strength 80 for resistance and at the same time do the work with as little bowing out of the flaps as possible. 85

In Fig. 7, we have shown a plan view of the case with the staple on one side in place. We will now describe how a large case may be sealed with the same anvil, for it is preferable not to bring the thickened portion 90 under the flaps for it bows them out. The condition of the case in Fig. 7 is, of course, slightly exaggerated for the purpose of illustration, but it shows the flaps are drawn tightly together when the staples on one side 95 are inserted. The case is then swung around upon a work table (not shown) and the staples at the opposite side are placed (Fig. 8) in the already described method. This pulls the flaps tightly together at the other 100 side.

It is very material to draw the flaps tightly together as the entry of dust and dirt is minimized the tighter the flaps are. It is customary to use two sets of flaps one 105 set over-lapping the other and the meeting edges of the inside set running at right angles to the meeting edges of the outside set. The inside set may be sealed in the same way as the outside set which is here 110 described.

In cases of small dimensions the flaps may be fastened, if desired, by using an anvil which is of sufficient length to run clear through the case; in larger cases it is better 115 practice to run the anvil about half-way through the one side and then run the anvil half-way through on the other side, the reason for this is that if the anvil were made of sufficient length to go completely through 120 it would have to be so thick that it would tend to bow the flaps out.

An extension *o* protrudes from the said upright *a* and under the horizontal arm *b*; a holder *p* straddles this. This holder *p* has a hand-screw *q* which bears against the abutment *r* located on the upright *a*. Inasmuch as the holder *p* is pivoted to the projection *o*, by turning the screw *q* against the abutment *r* the said anvil *n* is adjusted angularly 130

with respect to the upright and consequently may be adjusted with respect to the stitching head.

In the prior art, machines are shown with 5 flexing anvils but they are not designed to or capable of doing the clenching wholly alone but they are provided with a bed immediately thereunder which is designed to take the brunt of the blows from the fastener 10 setting mechanism. Other machines have also been proposed with rigid anvil arms but they can hardly be said to be blade anvils for they are altogether too thick. These machines are wholly unadapted to seal a ship- 15 ping case.

Some of the claims contain recitals of the position of the anvil relatively to surfaces thereunder for purposes of differentiation from the prior art, but it must not be understood that this is the only differentiation, because as already pointed out the anvil itself is a wholly different thing from any shown in the prior art; yet the differences reside in 20 dimensions which vary with the size of the work and consequently it is very difficult to structurally distinguish from what is old 25 without unduly limiting the invention.

In some cases containing such material, for instance, as tobacco, some little support 30 might be secured from the contents of the case without harming them, but such usage would be within the spirit of our invention for the principle of our invention would be, in the main, appropriated.

35 What we claim is:

1. The combination with a machine for driving metallic fasteners, of an anvil in the form of a blade of proportions so calculated with respect to the size of a fiber 40 shipping-case to be sealed as to underlie overlapping flap portions thereof without leaving them materially bowed out when the fastening has been done and the shipping case withdrawn from the anvil, and a support for rigidly holding one end of said anvil positioned with respect to the nearest surface under said anvil a sufficient distance to 45 accommodate the fiber shipping-case to be sealed, the said anvil being dimensioned and 50 constructed to be capable of taking the impact of the operating parts of the machine without support other than at its rigidly supported end.

2. The combination with a machine for 55 driving metallic fasteners, of an anvil in the form of a blade, a support for rigidly

holding one end of said anvil so as to allow the greater portion of the length of the anvil to be free at all times from all underlying portions of the machine, said blade being of 60 a thickness and construction to leave the overlapping flaps of a fiber shipping-case not materially bowed out when the fastening is done and the shipping-case is withdrawn from the anvil, and the said thickness, dimensions and construction of said blade being such as to secure support from the above-mentioned support to sustain the impact of the fastener driving mechanism of said machine. 70

3. The combination with a machine having an upright, a horizontal arm supported by the upright, a stitching head carried on the arm, a holder pivotally supported by said upright, and means for adjusting the 75 holder angularly with respect to the upright, of a blade-like anvil detachably supported in a rigid relation by said holder, the said blade-like anvil being supported somewhat above the nearest surface under the anvil 80 and extending from the said holder free of any other support to a position directly under the stitching head, substantially as described.

4. The combination with a machine for 85 driving metallic fasteners, of an anvil in the form of a blade whose construction is such that it is capable of perceptible flexure and yet is of sufficient rigidity without support thereunder to withstand impacts of the 90 operating parts of said machine in driving metallic fasteners, and means for supporting the anvil rigidly at one end and allowing it to project into free space.

5. The combination with a machine for 95 driving metallic fasteners, of a comparatively flexible anvil in the form of a blade or relatively thin strip, and means for rigidly supporting said anvil at one end, the dimensions and construction of said anvil being 100 such that it may perceptibly flex under the impact of the operating parts of said machine and yet be capable of clenching the fasteners wholly by the resistance afforded by said supporting means at the anvil's end. 105

In testimony whereof, we sign this specification in the presence of two witnesses.
